UNITED STATES PATENT OFFICE.

FRANK M. LEAVITT, OF NEW YORK, N. Y., ASSIGNOR TO THE E. W. BLISS COMPANY, OF SAME PLACE.

STEAM PUMPING-ENGINE.

SPECIFICATION forming part of Letters Patent No. 663,910, dated December 18, 1900.

Application filed January 30, 1899. Serial No. 703,773. (No model.)

To all whom it may concern:

Be it known that I, FRANK M. LEAVITT, a citizen of the United States, residing in New York, (Brooklyn,) in the county of Kings and State of New York, have invented certain new and useful Improvements in Steam Pumping-Engines, of which the following is a specification.

This invention relates to atmospheric or vacuum engines, and particularly to double-acting engines. Vacuum-engines are chiefly employed for small power purposes, such as pumping water for domestic establishments, for railway-tanks, shops, &c., or for driving small light machinery. As engines for such purposes are commonly operated where there is no licensed engineer, it is important for safety that the steam-pressure in the boiler be practically *nil* or only sufficient to cause a circulation of steam through the engine in starting. Hence such engines are operated entirely or almost entirely by atmospheric pressure due to the condensation of the steam admitted to the cylinder. It is important that an engine for use in domestic establishments should be of compact form, occupying as small floor-space as possible, and should be of such construction that it requires but little attention and at the same time be of low cost and efficient in operation. A further desirable feature is that the lubrication of the bearings should be facilitated and the leakage of oil prevented. My invention aims to produce an engine of this character; and it consists in the novel features hereinafter more fully pointed out in the claims.

The accompanying drawings show the preferred construction of engine embodying my present invention, wherein—

Figure 1 is a vertical mid-section. Fig. 2 is a front elevation. Fig. 3 is a vertical section of the lower part of Fig. 2, showing the arrangement of the condenser tubes, plates, and passages. Fig. 4 is an elevation of the engine and boiler connected. The remaining views are on a larger scale, of which Figs. 5, 6, 7, 8, and 9 are horizontal sections taken on the lines 5 5, 6 6, 7 7, 8 8, and 9 9, respectively, of Fig. 1. Fig. 10 is a vertical section taken on the line 10 10, Fig. 2, and showing the construction of the discharge-valve of the

air-pump. Fig. 11 is a vertical section on the line 11 11, Fig. 1, showing in detail the construction of the water-pump and air-pump and their connection with the piston-rod. 55 Fig. 12 is a similar section of part of Fig. 11, showing the water-pump plunger exposed for inspection. Fig. 13 is an enlarged vertical section taken on the line 13 13, Fig. 1, looking from the right; and Fig. 14 is a top view of 60 the nut used in connecting the pump-rod to the piston-rod.

The engine thus illustrated is a double-acting vacuum steam-engine having a surface condenser and a double-acting water-pump 65 and single-acting air-pump, which are arranged in line with the steam-cylinder.

Referring to the drawings, A designates the base, upon which is mounted a hollow standard B, which is adapted to support all of the 70 operating parts of the engine. The standard B has at its upper end an oil-chamber a, preferably cast integrally with said standard, a wall or partition b dividing the oil-chamber from the lower part of said hollow standard, 75 in which is located the condenser-chamber C, as will be hereinafter more fully described. The oil-chamber a is formed with an enlarged extension or compartment a', as shown particularly in Figs. 1 and 5. The crank-shaft 80 D is located chiefly in said oil-chamber, said shaft rotating in bearings c and c', that may, as shown, be formed integrally with the walls of said chamber. One end of said shaft projects out through the wall of said chamber 85 and carries the fly-wheel E and the other end extends into the compartment a' and is formed with the crank d.

Upon the top of standard B is mounted the steam-cylinder F, with its steam-chest G, which 90 are preferably of one piece. The steam-chest G is of usual construction, having the ports e and e' leading to the steam-cylinder, which are controlled by the ordinary slide-valve H. This valve is actuated by the eccentric I, secured on the shaft D by the nut f, the eccentric strap or ring being connected to the valve by the valve-rod H'. The steam-cylinder F is of peculiar construction and, together with the piston J, constitutes one of the features 95 of my invention. The upper head of said cylinder is in the form of a dome and extends 100

upwardly from the cylinder-walls, while the lower head F' is also of dome shape, but extends into the cylinder. The cylinder-head is preferably one integral casting, having below said dome-shaped portion a wall g , whereby is formed a chamber h . The piston-rod K passes down, as usual, through the lower head and the chamber h , which opens against the piston-rod, preferably at the upper end of the chamber. The piston J is dome-shaped, conforming to the heads of the steam-cylinder. The object of this peculiar construction of piston and cylinder is as follows: It is of importance in an engine of this class where the pressure is limited to avoid the use of packing wherever possible, consistent with the avoidance of undue leakage, in order to avoid the friction resulting from such packing. By forming the piston in the shape of a dome a broad bearing-surface is obtained, and by forming this bearing-surface with a number of circumferential grooves i the use of packing is avoided. The dome shape of the lower cylinder-head admits of the formation of the chamber h within it, and thus reduces the height of the engine, securing a compactness of construction which is of importance in an engine of this character. The chamber h is connected to the steam-chest by a duct j , by means of which live steam is conducted to said chamber and comes against the piston-rod. As before stated, it is important to avoid the use of packing in engines of this class, and this applies to the piston-rod, the ordinary stuffing-box for which is difficult to keep tight and the friction of which reduces the efficiency of the engine. In case of any leakage of air through such stuffing-box it partially destroys the vacuum and overtaxes the air-pump. A leakage of steam into the cylinder, however, is of slight consequence, as it can be easily condensed and disposed of by the air-pump. By the construction just described I not only do away with the friction of a stuffing-box, but effectually prevent any leakage of air into the cylinder around the piston-rod and provide that whatever leakage occurs into the exhaust will necessarily be of steam, which, as before stated, is of no consequence. The inner wall of the chamber h is preferably extended upwardly, surrounding the piston-rod, so as to form a neck through which the piston-rod works. Any water of condensation drains to the lower part of said chamber and is carried off by a pipe k , which may lead to the ash-pan of the boiler-furnace, as shown in Fig. 4, or to any other suitable waste.

By reason of the described construction the piston-rod works in the chamber h , whereby it is surrounded by an atmosphere of steam at a pressure slightly greater than that of the atmosphere—say, for example, two or three pounds—so that any leakage which occurs through the neck between said chamber and the space below the head will necessarily be a leakage of steam outwardly rather than air

inwardly. Such leakage, however, is of trifling amount, because the rod is a close working fit with the neck and the steam is under very little pressure. A similar neck separates the chamber h from the interior of the cylinder, so that any leakage into the cylinder, such as is liable to occur during the exhaust-stroke, is a leakage of steam from the chamber h instead of a leakage of air from the exterior. The means thus described for dispensing with a stuffing-box and protecting the exhaust against leakage of air is not herein broadly claimed, being the subject-matter of another application filed by me on January 18, 1899, Serial No. 702,498.

The piston-rod K extends downwardly through the compartment a' , passing through a stuffing-box L in the lower wall thereof. Said rod is connected in any suitable way to the crank d , the construction shown, which is preferred by reason of its compactness, being that of a slotted cross-head l , formed on the rod, with a sliding block m working in said cross-head, the crank-stud d turning in said block, whereby the crank-shaft is driven from the piston-rod in a usual manner.

The chamber a is designed to contain oil for the lubrication of the various bearings contained therein, the oil being preferably kept at about the level shown, so that at every revolution of the shaft D the crank d and block m and its slideway in the cross-head l will come in contact with the oil, and the eccentric also turns in the oil. The shaft-bearings $c c'$ and stuffing-box L will also be lubricated and enough oil will spatter or be thrown up to lubricate the valve-rod H' . Oil may be poured in by lifting off cover a^2 . A further object of the chamber a is to receive any water of condensation which may leak into it around the valve-rod H' and the piston-rod K . Such water will of course sink to the bottom of said chamber and eventually find its way out through the stuffing-box L . If the chamber a , therefore, is kept supplied with oil, the bearings and other frictional surfaces of the engine and pumps will need no attention, and this is a particular advantage where the engine is used in residences and other places where an engineer or skilled attendant is not employed.

As before stated, the lower part of the piston-rod extends through the stuffing-box L , and more or less oil and water of condensation will leak from the chamber through said stuffing-box. In order to prevent loss of oil and leakage of water, I secure to the piston-rod below said stuffing-box a basin n , which surrounds said rod and which is provided with a lip or spout n' . Beneath said basin is arranged a receptacle p , which is preferably cast in the standard B and which is adapted to receive the oil and water leaking into the basin n . Preferably the receptacle p is arranged directly beneath the spout n' , so that the drip from the latter falls directly into said receptacle. A cock p' may be arranged

in the wall of said receptacle p for the purpose of drawing off the oil and water therefrom.

I will now describe the condenser and air-pump.

The condenser-chamber C , as before stated, is formed by the hollow standard B and is divided from the oil-chamber a by the wall or partition b . The base A is formed with a depression in its top, which forms a chamber g , into which the exhaust-steam is led from the steam-cylinder by the pipe q' , as shown particularly in Figs. 2 and 4. Between the base and hollow standard are confined two plates M and O , which serve as condenser-tube plates. The inner tubes $r r$ of the condenser are mounted in the plate M and communicate with the chamber or space g . The outer tubes $s s$ of the condenser, which are closed at the top, are fixed at the bottom in the upper tube-plate O . Between the two plates is formed a chamber t , which communicates with the air-pump N by means of the pipe u , as shown particularly in Figs. 2 and 3. The two plates M and O are bolted or otherwise detachably secured between the base and the hollow standard, into the chamber C of which latter the tubes r and s extend. While I prefer to construct the base and tube-plates as shown, it is obvious that these parts may be formed in any way so that a chamber is provided which communicates with the inner tubes, and a second chamber is also provided, which communicates with the outer tubes, and that these two chambers have no connection between them except through the condensing-tubes.

The air-pump consists of a shell v , formed with a cylinder v' , which is arranged in line with the steam-cylinder, a plunger w , and the inlet and outlet valves x and x' . The cylinder is supported by a pendent arm or bracket secured to the water-pump shell in a manner to be described.

The construction of the valves x and x' is shown particularly in Figs. 10 and 11. They may be provided with the ordinary winged guides and with knobs or projections x^2 on top, which are designed to limit the upward movement of said valves by coming in contact with the valve-caps $y y$. These caps are preferably provided with central projections or knobs and are held firmly in position by yokes $z z$, each of which is pivoted on a bolt z' , passing through the pump-shell v beneath, and is provided with a vertical set-screw z^2 , which is adapted to be screwed down on the top projection of the cap y and by means of which an extremely tight fit is obtained, the cap being ground to its seat, or it may be luted or otherwise made tight. When it is necessary or desirable to examine these valves, the vertical screws are loosened and the yokes allowed to swing over past the caps, which are removed and the valves lifted out. The pump-plunger w is formed at its upper end with a cross-head P . This head is connected

to the steam piston-rod by means of two rods $P' P'$, which connect it with a cross-head P^2 on said piston-rod, as shown particularly in Fig. 11. By preference the cross-head P^2 is formed integrally with the basin n and its spout n' .

The course of the steam is as follows: Steam enters the valve-chest through the steam-pipe leading from the boiler and is admitted to the steam-cylinder through the usual cylinder-ports. After entering the exhaust-passage the steam flows down through exhaust-pipe q' to the chamber g of the condenser, where it rises through the inner condensing-tubes $r r$ until it reaches the top thereof, when it descends between the inner tubes and the outer tubes $s s$ and is condensed, and the water of condensation flows into the chamber t and thence to the air-pump through pipe u .

The water-pump Q is double-acting and is constructed with a shell Q' , which is preferably cast integrally with the standard. The pump-cylinder 15 is located vertically in said casting and in line with the piston-rod K and air-pump cylinder v' . The pump-rod 16 receives its movement from the piston-rod K , to which it is coupled. Said pump-rod 16 extends through a stuffing-box 17 and carries at its lower end the pump piston or plunger 18. Said stuffing-box 17 is secured in place by a ring or collar 19, which fits over the neck of said stuffing-box against a shoulder thereon and is held in position by set-screws 20, which screw into the pump-shell. The plunger 18 is provided with reversely-cupped packing-rings, which are confined in place in a usual manner.

The pump-rod 16 is coupled to the piston-rod K in the following manner: The piston-rod is provided with a central bore 21, which is of sufficient length and diameter to allow the pump-rod to slide up therein a sufficient distance to expose its plunger. The lower end of the piston-rod is screw-threaded externally, as shown particularly in Fig. 11. The upper end of the pump-rod is also screw-threaded to take a nut or screw-head 22. A coupling nut or union 23, having a socket at its lower part to receive the nut 22 and being screw-threaded at its upper part, is adapted to fit over said coupling-nut and screw onto the piston-rod K in the manner shown. The nut 22 is preferably provided with a pin 24, which fits into a hole in the end of the piston-rod to prevent the rotation of the nut and pump-rod during the screwing up of the union. When thus united, the nut 22 is held securely against the end of the piston-rod by the union 23, thus coupling the two rods together. In order that the nut or screw-head 22 may be clamped firmly upon the threaded end of the rod 16, I prefer to construct it as an expansible nut by splitting it, as shown in plan, Fig. 14, and I form its outer surface or the inner walls of the socket in the union 23, or both, of conical form, so that the act

of screwing up the union serves to compress the divided nut 22, so as to close it together and cause it to bind tightly upon the threaded end of the rod, whereby any turning of the 5 rod which might cause it to partially unscrew or to screw in too far is avoided. I do not wish to be limited to the particular connection here shown and described, as other connections may be used which accomplish the 10 same result. When it is desired to inspect the pump-plunger, the coupling-nut 23 is unscrewed from the piston-rod K and dropped down, and the nut 22 is then unscrewed and taken off, after which the coupling-nut may 15 be removed. The pump-rod is then pressed down to the bottom of its stroke and the stuffing-box 17 removed by unscrewing the set-screws 20. The pump-rod is then pushed up into the bore 21 of the piston-rod, exposing 20 the plunger, as shown in Fig. 12. Thus access may be had to the plunger-packing and the latter may be renewed.

The pump-shell has formed within it the chamber 25, which is located in front of the 25 pump-cylinder 15 and is connected to the water-supply by the pipe 26. The usual suction-valves 27 27 control the upper and lower outlets from said chamber 25, which outlets lead to the upper and lower passages 28 28. 30 The discharge-valves 29 29 control the flow through said passages 28 into the condenser-chamber C in a usual manner, as best shown in Figs. 1 and 13.

Openings are formed in the upper and 35 lower walls of the pump-shell, through which access can be had to the suction-valves 27 27. To form closures for said openings, upper and lower cap-plates 30 30 are used, each of which has formed on its inner side a circular flange 31, which extends around the stem of the valve and is designed to limit the movement of the valve, as shown. Said cap-plates are held in position by the bolts 32, which pass through said plates on opposite 40 sides of the pump-shell, said bolts being guided by lugs 33, formed on the pump-shell. Suitable openings are also formed in the sides of the pump-shell for access to the discharge-valves 29 29, and to form closures therefor the 45 caps 34 may be employed. These caps are arranged in pairs, each pair being connected by a yoke 35, as shown in Fig. 13. The yokes 35 are provided with central holes 36, and the pump-shell is also provided with a coincident hole 37. The caps 34 are held in position over the valve-openings by a bolt 38, passing through said holes in the yokes and 50 pump-shell.

The lower wall of the pump-shell is formed 60 with a hole 39, which is of a diameter sufficient to allow the withdrawal of the pump plunger and rod and is closed by a cap-plate 40, to the under side of which is secured the depending arm or bracket 41, which forms a 65 support for the air-pump cylinder v'. The said cap-plate is located between the rods P' P', which connect the air-pump plunger to

the piston-rod, as before described, and is provided with the extensions 42, having the holes 43, Fig. 9, by means of which it is bolted 70 to lugs 44 on the under side of the pump-shell. The cap-plate 40 when in position is not at right angles to the pump-shell, but is turned to avoid the connecting-rods P' P', as shown in Figs. 8 and 9. The pump rod and 75 plunger may be removed or inserted through the hole 39; but as this will necessitate the entire disconnection of the air-pump I prefer to do this by the more convenient means hereinbefore described. 80

To enable the shaft D to be inserted and removed, I provide the front of the chamber a a' with a large opening closed by a disk or cover b'. By removing this access is had to the crank d. By taking off the fly-wheel and 85 through the top opening slackening off the nut f and the eccentric and then removing the block m and setting the crank at half-throw the shaft D may be removed through the slot in the head l and through the front opening. 90

It will be seen that by my invention I produce a double-acting vacuum-engine which is of simple and economical construction and efficient in operation. The connection of the operating-rods of the water and air pumps 95 directly with the piston-rod dispenses with separate connections with the shaft and their bearings, which is a very desirable feature. The whole engine is compactly arranged, being designed to occupy as small floor-space 100 as possible, and the bearings are all inclosed and protected from dust, &c. All of the frictional surfaces are practically self-lubricating, and at the same time there is no leakage of oil on and about the engine. For these 105 reasons my invention is particularly adapted for use in residences, where it is essential that an engine should be capable of efficient operation with little or no attention. 110

What I claim is--

1. A vacuum pumping-engine comprising an upright hollow standard having within it a condenser, the engine-cylinder mounted on said standard, above said condenser, the pump-cylinder mounted on the side of said standard below and in line with the engine-cylinder, a direct connection between the engine-piston and pump-plunger, a rotary shaft mounted between said cylinder and pump, connected to the engine-piston, and driven 115 thereby, having bearings on said standard above said condenser, and the engine-valve driven from said shaft.

2. A vacuum pumping-engine, comprising a steam-cylinder, a piston-rod working in 125 said cylinder, a water-pump located under said cylinder in line therewith, the operating-rod of said pump being connected to said piston-rod, an air-pump located below and in line with said water-pump, a cross-head connected to said piston-rod, a cross-head carried by the air-pump plunger and two rods connecting said cross-heads, arranged on opposite sides of the water-pump. 130

3. In a pumping-engine, the combination with a steam-cylinder and a water-pump located in line with said cylinder, of a piston-rod having a central bore, a pump-rod carrying a plunger and having its upper end connected to said piston-rod, and adapted when disconnected from said piston-rod to slide up into said bore a distance sufficient to expose said plunger.

10 4. In a pumping-engine the combination with a steam-cylinder and a water-pump located below said cylinder and in line therewith, of a piston-rod having a central bore, a pump-rod carrying a plunger, and a coupling adapted to detachably connect the pump-rod to the piston-rod, said pump-rod being adapted when disconnected from said piston-rod to slide up into said bore a distance sufficient to expose said plunger.

15 5. In a pumping-engine, the combination with a steam-cylinder and a water-pump located below said cylinder, and in line therewith, of a piston-rod having its lower end screw-threaded and formed with a central bore, a pump-rod adapted to slide into said bore, and having its upper end screw-threaded, a nut adapted to screw on said pump-rod, and a union adapted to unite said nut to the end of the piston-rod, whereby when said nut 20 and union are unscrewed the pump-rod may be elevated into the bore of the piston-rod, to get access to the pump-plunger.

25 6. In a pumping-engine, the combination with a steam-cylinder and a water-pump located below said cylinder, and in line therewith, of a piston-rod having its lower end screw-threaded and formed with a central bore, a pump-rod adapted to slide into said bore, and having its upper end screw-threaded, a divided nut adapted to screw on said pump-rod, and a coupling-nut adapted to fit over said divided nut and screw on the end of the piston-rod, said nuts being so formed that the divided nut is cramped about the 30 end of the pump-rod and held firmly against the piston-rod, after said coupling-nut is screwed in place.

35 7. In a pumping-engine the combination with a piston-rod, an oil-chamber inclosing 40 bearings for the crank-shaft and crank through which chamber said piston-rod extends, and a stuffing-box for said piston-rod located at the bottom of said chamber, of a basin surrounding and secured to said rod below said stuffing-box, adapted to receive any leakage from said stuffing-box, and a receptacle into which said leakage is conducted from said basin.

45 8. In a pumping-engine the combination with a hollow standard, an oil-chamber mounted thereon, a piston-rod extending through said chamber, and a stuffing-box for said piston-rod, located at the bottom of said chamber, of a basin surrounding and secured to 50 said piston-rod below said stuffing-box, and having a lip or spout, said basin being adapted to receive any leakage through said stuff-

55 ing-box, and a receptacle formed in said hollow standard, to which said leakage is conducted.

60 9. In a pumping-engine the combination with a hollow standard, an oil-chamber mounted thereon, a piston-rod extending through said chamber, and a stuffing-box for said piston-rod, located at the bottom of said chamber, of a basin surrounding and secured to 65 said piston-rod below said stuffing-box, and having a lip or spout, said basin being adapted to receive any leakage through said stuffing-box, and a receptacle formed in said hollow standard and located under said basin, into which said leakage drips from said basin.

70 10. In a vacuum-engine, the combination of a steam-chest and a steam-cylinder having a lower dome-shaped head having within it a live-steam chamber through which the piston-rod extends, and a steam-port leading to 75 said chamber.

80 11. In a pumping-engine, the combination of a steam-chest and a steam-cylinder having a lower dome-shaped head having within it a live-steam chamber through which the piston-rod extends, and formed with a neck extending upwardly and surrounding said piston-rod, and a steam-port leading to 85 said chamber.

90 12. In a pumping-engine, the combination of a steam-chest and a steam-cylinder having a lower dome-shaped head having within it a live-steam chamber through which the piston-rod extends, and formed with a neck extending upwardly and surrounding said piston-rod, a steam-port leading to 95 said chamber, and a drainage-pipe adapted to draw off any water of condensation formed in said chamber.

100 13. In a pumping-engine the combination with the piston-rod and the main shaft having a crank engaged by said rod, of an oil-chamber inclosing said crank and having bearings for said shaft, said shaft and bearings being so formed that the shaft may be removed endwise from said bearings without displacing the latter, and said chamber having a hand-hole opposite said crank to permit the removal of the shaft from its bearings, and a cover for said hand-hole.

110 14. In a pumping-engine, the combination of a main shaft, having a crank at one end, an oil-chamber inclosing said crank, and having bearings for said shaft, said chamber having a hand-hole opposite said crank to permit the endwise removal of the shaft from its bearing, a cover for said hand-hole, and a piston-rod extending within said chamber and engaging said crank, whereby upon removal 115 of the cover and disengagement of said crank and rod, the shaft may be removed endwise from its bearings through said hand-hole.

120 15. In a pumping-engine, the combination of a shaft having a crank, a piston-rod for rotating said shaft having a slotted cross-head, its slot large enough to admit said crank-shaft and crank to pass through it, and a block sliding in said cross-head and engaging

- said crank and adapted to be moved out of engagement therewith without disturbing said piston-rod, whereby upon removal of said block the shaft may be withdrawn from its bearings through the slot in said cross-head.
16. In a pumping-engine, the combination with a chamber having bearings for a shaft, and a shaft mounted in said bearings and having a crank at its outer end, of a piston-rod 10 having a slotted cross-head, its slot large enough to admit said crank-shaft to pass through it, a block sliding in said cross-head and engaging said crank, said chamber having a hand-hole opposite the end of said shaft, 15 and a cover for said hand-hole, whereby upon removal of said cover and sliding block the shaft may be removed from said chamber through the slot in said cross-head without disturbing the piston-rod.
17. In a pumping-engine, the combination with a steam chest and cylinder, of a chamber located beneath said chest and cylinder, a valve-rod and piston-rod passing from said chest and cylinder into said chamber, and 20 said piston-rod passing through the bottom of said chamber, a stuffing-box for said piston-rod located at the bottom of said chamber,

and a basin located on said piston-rod below said stuffing-box, whereby any water of condensation escaping around said rods will be 30 caught in said chamber and pass through said stuffing-box into said basin.

18. In a pumping-engine, the combination with a steam chest and cylinder, of a chamber located beneath said chest and cylinder, 35 a valve-rod passing from said chest into said chamber, a piston-rod passing from said cylinder into and through said chamber, a stuffing-box for said piston-rod located at the bottom of said chamber, a basin located on said 40 piston-rod below said stuffing-box, and a receptacle below said basin, whereby any water of condensation escaping around said rods will be first caught by said chamber, then pass through said stuffing-box into said basin, 45 and flow from said basin into said receptacle.

In witness whereof I have hereunto signed my name in the presence of two subscribing witnesses.

FRANK M. LEAVITT.
